UNITED STATES PATENT OFFICE

DAVID B. ROBERTS, OF HARTFORD, CONNECTICUT

OIL BURNER

Application filed January 21, 1928. Serial No. 248,484.

The main object of my invention is to make unnecessary the remote location from an oil burner of the fuel supply, and thus get rid of serious objections to the use of oil burners for that reason. I attain my object and secure other advantages, by placing the fuel supply, including the carburetor immediately adjacent the pump (which is located at the base of the furnace or heater) and preferably 10 below the pump, and a part thereof or attached to it and thereby getting better results as the fuel is delivered to the burner immediately after carburetion and therefore without opportunity for it to change.

15 My invention consists in whatever is the construction that has the characteristics mentioned, and whatever is described by or is included within the scope of the claim.

In the drawings the figure is a vertical section of an oil burner embodying my invention, with parts in elevation.

The general construction shown in the drawing is similar to that of my application, No. 248,483, filed Jan. 21, 1928, executed the 20 same date herewith which includes a furnace having an ash-pit, 10, above which is mounted a fire box, 11, having a fire-clay retaining wall, 12, a pump unit, 13, of the intermeshing gear type and an electric motor, 14, supported by the top plate of the pump unit which motor has for an armature shaft a vertical hollow shaft, 15, to the top of which is attached a nozzle, 16, to which fuel is delivered by being passed from the pump through said 25 hollow shaft. Immediately or directly below the pump unit I locate or place the carburetor 17, so that fuel ready for combustion is taken directly therefrom and delivered by the pump to the nozzle, the carburetor being of any suitable construction and which by a pipe, 18, is connected with an oil tank.

I claim:

30 In a liquid fuel burning apparatus, the combination of a motor, a pump directly below the motor, a fuel supply on top of which the pump directly rests and takes fuel directly therefrom and a fuel distributing means, motor, pump and fuel supply being joined together to constitute a single unit, a combus-

tion chamber in which the distributing means is located and a working chamber below the combustion chamber and containing the other elements and having side walls which surround said other elements and which form 35 the floor base of the apparatus.

In testimony whereof I hereunto affix my signature.

DAVID B. ROBERTS.
